GUSTAV HOLTZ AND CALVIN GRESS, OF GOULDSBORO, PENNSYLVANIA.

SELF-CENTERING ICE CHUTE AND RUN.

Application filed March 12, 1920. Serial No. 365,260

To all whom it may concern:

Be it known that we, GUSTAV HOLTZ and CALVIN GRESS, citizens of the United States, residing at Gouldsboro, in the county of Wayne and State of Pennsylvania, have invented new and useful Self-Centering Ice Chutes and Runs, of which the following is a specification.

This invention relates to ice chutes and runs. An object of the invention is to provide an ice chute which will center the cakes of ice as they slide by gravity down to the run, and which will insure the ice traveling midway of the runway without colliding with the sides thereof. It is then within the province of this invention to provide a combined chute and runway, or track, for ice, so constructed that however a cake of ice may be handled it will be centered by the chute as it travels down the same and will pass on to the runway for the entire length thereof, with a minimum of resistance offered to its passage.

A further object is to provide a chute and runway in such relation to each other that the ice will be grooved as it passes from the chute to the runway, which grooves will prevent the ice from moving from side to side of the runway.

A further object is to provide an ice chute and run which is especially useful under winter conditions.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing, Fig. 1 is a top plan view of an ice chute and a portion of a runway constructed in accordance with this invention.

Fig. 2 is a side elevation of the same.

Fig. 3 is an end elevation of one of the sections of the runways.

X represents the ice chute which is connected at its discharge end to a runway Y, comprising sections Y¹, Y², etc. The receiving end of the chute is secured upon a support Z which may be adjacent a runway

or conveyor in an ice house. The chute X is inclined as shown in Fig. 2, and is tapered as Fig. 1 depicts, while the runway Y leads the ice along the floor of a room of the ice house and is therefore substantially horizontal.

The numeral 10 refers to the side bars of the chute which further comprises ties 11, 12, 13 and 14, fixed to the side bars 10 at spaced intervals. The side bars 10 converge towards each other from the receiving end of the chute at Z to the discharge end thereof, where it is joined to the run. Running longitudinally of the chute are T-bars 16 set in notches, or seats, 15 cut in the ties of the chute. The T-bars form a track for the cakes of ice and there may be any number of them secured upon the ties. The free edges of the webs of the T-bars are uppermost so that the ice cakes slide over these edges. The T-bars 15 converge towards a common point, and the point of convergence of the T-bars and of the side bars 10 is preferably the same. This placing of the T-bars on the chute results in their ends being spaced farther apart at the receiving end of the chute than at the discharge end. Each of the T-bars stops short with the end tie 11 for a purpose to be made plain.

The first section Y¹ of the runway is detachably secured to the discharge end of the chute by any desirable means. The drawing shows a strap 17 fixed to the lower ends of the side bars 10 which strap has a perforation to receive a finger 24 of a strap 23. Instead of this means of connecting the chute with the runway other means might be employed, the particular means forming no part of the present invention. In any case, however, the first section of the runway is held spaced from the lower end of the chute to the degree shown in the drawing.

The run sections each comprise side bars 18 which side bars have less height than the side bars 10, end ties 19, intermediate ties 20 and T-bars 22. The latter are set in notches, or seats 21 cut in the ties and are secured to the ties by any preferred means. The T-bars 22 are secured in a position similar to the T-bars 16 except they are parallel to each other. The ends of the T-bars of the first section Y¹, where the same is joined with the chute stop short with the end tie 19, leaving a gap or space between the T-bars of the chute and of said section. On the other hand the T-bars of the runways and sections where adjacent, may run substan-

tially continuously as do the rails of sections Y^1 and Y^2 of the drawing in Fig. 1.

As the ice travels along the conveyor or runway adjacent the support Z an operator will hook the cakes and throw them upon the chute. The chute is so constructed that it delivers the ice cakes in a line medial of the runway. The taper of the chute and the convergence of the T -bars thereof brings about this result. As the ice reaches the lower end of the chute it must pass over the gap or interval between the chute and the first section of the runway. Now the ice chute has a greater number of T -bars to form its track, and each of these T -bars is out of alignment with any of the T -bars of the runway. There will be preferably one more T -bar provided for the track of the chute than for the track of the runway. In the drawing five T -bars are shown on the chute and four on the run. The outer bars of the chute lie outside of the outer bars of the run. The effect of this construction, in connection with the incline of the chute and with the gap between the chute and run, is to make the ice hit the ends of the webs of the T -bars on the run, whereupon grooves are formed in the ice cake. These grooves guide the ice cake as it passes over the runway and prevent the ice from colliding with the sides of the same. In order to bring about this grooving effect it is absolutely necessary to have each T -bar of the chute out of alignment with any of the T -bars of the run, and it is further necessary to have the outer T -bars of the chute outside of the outer T -bars of the run. The free edges of the webs of the T -bars are blunt, the T -bars employed being the ordinary ones of commerce.

A feature of this invention is the simplicity of construction and the ease with which it may be put together. The framework of the chute and runway is preferably of wood, and the rails being ordinary T -bars are obtainable everywhere. No skill is required to spike down the T -bars on the ties in proper position, while an ordinary blacksmith may make the connecting elements 17 and 23 which hold the sections of the runway as well as the runway and chute together.

So far as we know we are the first to provide a self-centering ice chute particularly adapted for winter weather which will, no matter how carelessly the ice cakes are handled, always deliver the same in a line medial of the runway and which makes impossible any side movements of the ice cakes when once delivered down the runway.

What is claimed is:

1. In combination, an ice chute tapered from its receiving end to its discharging end, an ice run joined thereto but separated by an interval therefrom, and means on

the run for cutting grooves in the ice as it passes over said interval.

2. In combination, an ice chute comprising a frame and rails laid longitudinally of the frame, and an ice run similarly made and disposed with one end adjacent the end of the chute with a space separating the ends of the rails of the chute and of the run, the frame being tapered from its receiving end to its discharging end, the width of the run approximating the width of the discharge end of the chute, the rails of the chute and run being non-aligning.

3. In combination, an ice chute made up of a frame and longitudinally extending rails, the rails converging toward a common point, and an ice run connected with that end of the chute toward which the rails converge and having similar but parallel rails.

4. In combination, an ice run, an ice chute discharging into the ice run and made up of a frame and rails, the parts of the chute being so positioned as to deliver centrally of the run a cake of ice placed upon the chute.

5. In combination, an ice chute having rails converging toward the discharge end thereof, said rails ending with the chute; and an ice run having rails spaced apart at their ends from the rails of the chute.

6. In combination, an ice chute having a plurality of rails spaced apart but converging toward the discharge end of the chute; and an ice run with similar rails and joined to said chute end, the rails of the chute being more numerous than the rails of the run.

7. In combination, an ice chute having a plurality of rails spaced apart but converging toward the discharge end of the chute; and an ice run having rails and joined to said chute end, the outside rails of the chute being outside the corresponding rails of the run.

8. In combination, an ice chute, and an ice run connected thereto, both of said elements having rails, the rails of the ice run being spaced from the chute rails as well as from each other and being out of alignment with the chute rails.

9. A self-centering ice chute and run comprising a chute tapered toward its discharge end, rails on the chute converging toward that end but spaced apart; and an ice run fixed to the discharge end of the chute and having parallel rails longitudinally thereof, the rails of the chute being spread over a greater lateral area than the rails of the run.

10. In combination, an ice chute having converging sides, a plurality of rails on the chute converging in a like manner to the sides thereof, and an ice run having parallel rails, the ice run being adjacent

the end of the chute and the ends of the chute rails being spaced from the ends of the rails of the run, whereby the chute delivers ice cakes centrally of the run.

5 11. In combination, an ice chute having a plurality of rails converging toward the discharge end of the chute, and an ice run having parallel rails, the run being located adjacent the end of the chute with the rail

10 ends of the chute and run spaced apart, the

ends of the rails of the run being intermediate the rails of the chute so that the ends of the run's rails cut grooves in ice cakes descending upon the run from the chute.

In testimony, that we claim the foregoing as our own, we have hereto affixed our signatures.

GUSTAV HOLTZ.
CALVIN GRESS.
